(57) **CLAIM**

The ornamental design for a double-side solar cell, as shown and described.

DESCRIPTION

FIG. 1 is a front elevational view of a first embodiment of a double-side solar cell showing our new design; FIG. 2 is a rear elevational view thereof; FIG. 3 is an enlarged view of portion 3 in FIG. 1; FIG. 4 is an enlarged view of portion 4 in FIG. 2; FIG. 5 is a front elevational view of a second embodiment of the double-side solar cell; FIG. 6 is a rear elevational view of FIG. 5; FIG. 7 is an enlarged view of portion 7 in FIG. 5; and, FIG. 8 is an enlarged view of portion 8 in FIG. 6. There is no substantial thickness of the claimed design and all elements of the claimed design are flat and coplanar.
